UNITED STATES PATENT OFFICE

PAUL E. KLOPSTEG, OF CHICAGO, ILLINOIS, ASSIGNOR TO CENTRAL SCIENTIFIC COMPANY, A CORPORATION OF ILLINOIS

ELECTROMAGNETIC DEVICE

Application filed December 12, 1929. Serial No. 413,659.

The student of physics and electricity often finds it difficult to grasp the fundamental concepts of electromagnetism, and it is one of the primary objects of this invention to provide apparatus of exceedingly simple design which may be used to demonstrate in an elementary and convincing manner the principles which underlie the electric motor, the dynamo and the magnetic brake.

Other and further objects and advantages will become apparent as the disclosure proceeds and the description is read in conjunction with the accompanying drawings, in which

Fig. 1 is a plan view of the apparatus; and Fig. 2 is a longitudinal, sectional view of the same taken on the line 2—2 of Fig. 1.

About a century ago, the scientist Barlow produced rotation in a star wheel by causing an electric current to traverse radially over the wheel while placed between the poles of a horse shoe magnet.

A few years later, Faraday discovered that he could produce an electric current by rotating a copper disk between the poles of a steel magnet or electromagnet, the current flowing from shaft to rim, or vice versa according to the sense of rotation. Sliding contacts were used on the shaft and the periphery of the disk to conduct away the current generated.

A rotating copper disk placed in a magnetic field at right angles to the plane of the disk has for many years been used to demonstrate the operation of Lenz's law and the resultant effect of a magnetic brake.

This invention combines into one apparatus a structure especially adapted to the requisites of pedagogics which can be used to demonstrate the classical experiments referred to above of Barlow and Faraday and the operation of Lenz's law.

This specific illustration and correspondingly specific description are used for the purpose of disclosure only and are not to be taken as imposing a limitation upon the scope of the invention except as required by the prior art.

The apparatus in one of its forms comprises a base 10 preferably of wood, pro-

vided with knobs 11 at its four corners, which give to the base a convenient clearance from its means of support. A permanent magnet 12, preferably of chrome steel, is removably secured to the base by clamps 13 and 14 which are U-shaped in form and have their upper arms of sufficient length to engage the upper face of the magnet as at 15. The clamps are fastened to the base by countersunk bolts 16 provided with securing nuts 17 and thumb nuts 18.

The ends of the magnet 12 are brought close together at 19 and a copper disk 20 is mounted in a jaw lever 21 for rotation between the poles of the magnet. Frictionless conical bearings 22 are provided on the jaw arms for engaging the shaft 23 of the disk, and have lock nuts 24 to maintain proper adjustment.

A U-shaped fulcrum piece 25 secured to the base by a screw 26 carries the lever 21 by means of the stud screws 27 and permits the disk to be raised out of the magnetic field by simply applying pressure on the end of the lever. A pin stop 28 serves to fix the normal position of the disk.

The base 10 is provided with a mercury trough 29 into which the rotating disk 20 dips and electrical connection is made between the mercury in the trough and the binding post 30 by a screw 31 and conductor 32. The shaft 23 of the rotating disk 20 is in electrical connection with a second binding post 33 through the lever 21, fulcrum 25, screw 26 and a conductor 34. In this way, an electrical current can be made to pass radially through the disk from the shaft to the periphery, and vice versa.

When the apparatus is used as an elementary electric motor, the binding posts 30 and 33 are connected to a suitable source of current, such as a six volt storage cell, through a rheostat capable of carrying a fairly large current. A carbon compression rheostat is well suited for this purpose. When the current is turned on, the disk will rotate in a direction depending upon that of the magnetic field and of the current. A reversal of direction of either the magnetic field or the driving current will result in a rotation of the disk in an opposite direction, while a reversal of both will leave the rotation unchanged.

A radial stripe 35 on the disk aids in clearly showing the rotation of the disk.

Faraday's dynamo experiment with a rotating copper disk may be readily shown by connecting the binding posts 30 and 31 to a galvanometer and then spinning the disk by hand. A current is thereby induced which may be detected by the galvanometer. At constant rotational speed, a steady deflection will be registered on the galvanometer, its magnitude depending upon the strength of the magnetic field and the speed of rotation.

The magnetic brake effect may be clearly shown by this apparatus by setting the disk into rapid rotation when tilted out of its normal position and then lowering it into the magnetic field. In this experiment, the mercury contact has no importance and the braking action is caused solely by the fact that a conductor is being moved across a magnetic field. By the operation of Lenz's law, currents are induced which tend to oppose the movement of the conductor, which in the case of a rotating disk are called eddy currents.

25 Inasmuch as the magnet 12 may be readily removed from the base, it is an easy matter to reverse the magnetic field by inverting the magnet, which will cause a rotation of the disk in the opposite direction in the motor experiment and in the dynamo experiment will cause the galvanometer to be deflected on the other side of the zero mark. The mercury contact which engages the periphery of the rotating disk provides a frictionless electrical contact which enables a more striking demonstration of the motor and dynamo experiments to be made.

The fact that the disk may be readily moved in and out of the magnetic field provides a 40 convenient structure for making the experiments and is exceptionally useful in the magnetic brake experiment.

I claim as my invention:

45 1. An electro-magnetic device comprising in combination a base, a mercury trough in the base, a rotatable metallic disk dipping in the mercury, bearings for the disk, means for bodily lifting the disk and bearings from the trough, and a permanent magnet having 50 its poles on opposite sides of the disk.

2. An electro-magnetic device comprising in combination a metallic disk, a magnet having its poles on opposite sides of the disk, and means for temporarily removing 55 the disk from the magnetic field, including a lever rotatably carrying the disk.

3. In a device of the class described, the 60 combination of a rotatable disk having an axial hub, means for setting up a magnetic field through the disk, and a fulcrum support equipped with frictionless bearings engaging the hub adapted to raise and lower the disk from the magnetic field.

4. An electro-magnetic device comprising 65 in combination a rotatable metallic disk, a

bifurcated lever carrying the disk, a fulcrum for the lever whereby the disk may be raised and lowered, a sliding contact for the periphery of the disk, adapted to be connected to an external circuit, and means for creating a magnetic field intermediate the sliding contact and the center of the disk.

5. An electro-magnetic device comprising a base, a mercury contact in the base, a rotatable metallic disk dipping in the mercury, 75 means for connecting the mercury contact and the disk hub to a source of electrical energy to conduct a current radially through the disk, means for creating a magnetic field intermediate the mercury contact and the disk hub, and a bifurcated lever carrying the disk adapted to be rocked upon its support to raise the disk out of the magnetic field.

6. In an electro-magnetic device, the combination of a base, a horseshoe magnet 80 removably secured to the base, a metallic disk mounted for rotation between the poles of the magnet and means supported on the base for removing the disk from and reinserting the same in the field of the magnet.

7. In a device for demonstrating certain fundamental principles of electro-magnetism, the combination of a base, a lever support mounted on the base adapted to pivotally support a lever, a lever carried by the support equipped with arms having frictionless bearings, a metallic disk mounted between the arms of the lever and rotatably supported thereby, means for creating a magnetic field through the disk when the latter 95 is in its normal operative position, said disk being adapted to be raised from the magnetic field when the lever is rocked on its fulcrum.

8. In a device for demonstrating Barlow's wheel, Faraday's disk and the operation of 100 Lenz's law, the combination of a base, a mercury trough in the base, a rotatable metallic disk dipping in the mercury, means for creating a magnetic field intermediate the mercury trough and the disk hub, and bearing supports for the disk adapted to be bodily lifted with the disk from the magnetic field without disturbing the rotation of the disk.

In testimony whereof, I affix my signature. 115
PAUL E. KLÖPSTEG.
